(57) **CLAIM**

The ornamental design for a wheel, as shown and described.

DESCRIPTION

FIG. 1 is a front left perspective view of a wheel according to the present invention.

FIG. 2 is a front view of the wheel shown in FIG. 1; and, FIG. 3 is a left side view thereof, the right side view being a mirror image thereof.

In the Figures, any broken lines form no part of the present invention, but are instead included to show environmental structure.

1 Claim, 3 Drawing Sheets

FIG. 1

FIG. 2

FIG. 3
